CLAIM

The ornamental design for a dust bucket lid for a dust cyclone, as shown and described.

DESCRIPTION

FIG. 1 is a perspective environmental view of a dust-bucket lid for a cyclonic dust collector, showing our new design.

FIG. 2 is a top plan view thereof;

FIG. 3 is a bottom plan view thereof;

FIGS. 4 to 7 are a front elevational view thereof; a left-side elevational view thereof; a rear elevational view thereof and a right-side elevation thereof; and,

FIG. 8 is a bottom perspective view thereof.

The cyclonic dust collector and bucket shown in broken line form no part of our design. The center opening and the bolt holes surrounding it, shown in broken line and the latch and opposing hook member, shown in broken lines, do not form a part of our claimed design.
